C. M. SEARL

LAST

Original Filed April 21, 1924

INVENTOR.
Clinton M. Pearl,
BY *Farlinn & Farlinn,*
ATTORNEYS.

UNITED STATES PATENT OFFICE.

CLINTON M. SEARL, OF PORTSMOUTH, OHIO, ASSIGNOR TO THE VULCAN LAST COMPANY, OF PORTSMOUTH, OHIO, A CORPORATION OF OHIO.

LAST.

Original application filed April 21, 1924, Serial No. 707,796. Divided and this application filed November 24, 1924. Serial No. 751,766.

To all whom it may concern:

Be it known that I, CLINTON M. SEARL, a citizen of the United States, residing at Portsmouth, in the county of Scioto and 5 State of Ohio, have invented certain new and useful Improvements in Lasts, of which the following is a specification, reference being had therein to the accompanying drawing.

10 My invention relates to an improvement in lasts, and is particularly directed to lasts of the divided type—that is to say, to that type of last which is divided into two parts, a toe part and a heel part, movable relatively to each other to collapsed and extended positions. The present application is a division of my application filed April 21, 1924, Serial No. 707,796.

It is desirable in lasts of this type that 20 the last be capable of being easily collapsed so that it may be removed from a shoe without injury to the lining of the shoe and without stretching the shoe out of place.

In lasting a shoe the last is held upside 25 down—that is, with the sole side uppermost—and inasmuch as a great deal of pressure is put on the toe of the last during the lasting operation, this tends to collapse the last, and consequently one of the objects of my 30 invention is the provision of a construction in which the last is capable of withstanding the stresses to which it is subjected during the lasting operation without collapsing, but may be readily collapsed by the operator 35 when desired.

In one form of last now in extensive use, the fore part and heel part are attached to each other by a link attached to the fore part and heel part by pins so located relatively that a line drawn through their centers will fall above the axis on which the last parts move when the last is collapsed and below this point or axis when the last is extended.

45 In such a construction, the greater the distance the pins are below the axis of the last when the last is extended, or the greater the distance they are above the axis of the last when the last is collapsed, the more resistance the last will offer to collapse or extension, but this distance is limited inasmuch as the pins must be located in the last body itself, and in the case of wooden lasts the pins must be kept

55 at an appreciable distance from the bottom or sole face owing to the danger of splitting the last when the same is in use or when being moved from extended position to collapsed position or vice versa.

In the present construction I have provided an arrangement for attaching the two last parts to each other whereby an effect 60 is obtained which is as efficient as the lowering of the pins in the above-outlined construction to the danger point, the resistance 65 to collapse or extension offered by my last being very materially increased, without, however, necessitating placing of any pins at a point where they are likely to cause the last to split.

70 It is one of the especial objects of my invention to provide a last in which the last parts are held together under tension and not simply held in expanded or collapsed position under tension.

75 It is a further object of my invention to hold the last parts together by means employing a lever, with the parts constantly under tension.

80 It is a still further object of my invention to hold the parts of the last together under tension with the parts so arranged that the tension will assume its maximum when the parts are either in their fully expanded or fully collapsed position.

85 It is an additional object of my invention to provide the holding together of the parts under tension and to associate therewith a lever, the parts being so arranged that the tension will achieve its maximum at the 90 completely expanded or collapsed position of the last parts. It will be realized that the tension may be created by a variety of means which may be very compressible or expandable, and that the details of creating 95 this condition are not essential.

It is a further object of my invention to provide such mechanism to hold the parts of the last together under tension that it 100 will not be necessary to have resilient links or resilient anchor pins. Such means are eliminated and the same results are obtained.

It is a further object of my invention to provide the holding of such parts together under tension and the increasing of this 105 tension at extreme positions together with means to lock the parts in extended position by such tension means to resist the

pressure, tending to collapse the last imposed on the bottom of the toe member in constructing the shoe thereon until such tension means is overcome by the operator breaking the last.

In the accompanying drawing I have shown a sectional view illustrating my invention.

In the drawing I provide a heel portion 1 and a toe portion 2, these two portions being divided along the arcuate cut 3, the center of which is at 4. Pivoted to the heel part 1 by a pin 5 is a lever 6 and pivoted to the toe part 2 is a similar lever 7, this lever being pivoted to the toe part by the pin 8. These two levers are substantially triangularly shaped and the pin 5 above referred to passes through the lower extremity of the base of the lever 6 while the pin 8 passes through the lower extremity of the base of the lever 7. Extending through the apex of the lever 6 and the apex of the lever 7 and pivotally attached thereto by pins 9 and 10 respectively, is a link 11. This link is provided intermediate its ends with a pin 12 which extends transversely of the link and passes through a slot 13 in a pin 14 which extends substantially vertically of the last. Attached to the upper end of the pin 14 is a plate 15 and attached to the ends of this plate are two links 16 and 17, the link 16 being attached to the upper extremity of the base of the lever 6 while the link 17 is attached to the upper extremity of the base of the lever 7.

Mounted on the pin 14 and interposed between the plate 15 and the upper edge of the link 11 is a coil spring 18 always under compression.

With the parts in the full-line position shown in the drawings, the spring 18 is acting in a direction to swing the levers 6 and 7 about their respective pivots 5 and 8, but inasmuch as these two levers are tied together by the link 11 the result of this action of the spring is to tend to shorten the distance between the pins 5 and 8 to thereby hold the last parts in collapsed position under tension, the centers of the pins 5 and 8 lying below the center or axis 4 of the last.

When the last parts are moved to the dotted-line position of the drawing, the

spring 18 is exerting a pressure in a direction to tend to shorten the distance between the pins 5 and 8. A line passing through the centers of these pins at this time, however, falls above the axis 4 of the last, with the result that the last parts will be held in collapsed position under tension.

It will be apparent that I have provided a last structure wherein the last parts are held in extended position and in collapsed position under tension, thereby providing a structure which will successfully withstand accidental collapse or extension of the last parts when the same are in use in the manufacture of shoes. It will be seen also that in my invention I provide a structure in which the force exerted on the last parts to hold the last in extended and in collapsed position is of some magnitude, my improved construction being such, however, that this increase in force is provided without weakening the last. In other words, more power is available for holding the last parts in adjusted position due to my improved structure than is possible in lasts as now manufactured.

It will be seen also that I have provided a last structure wherein the last parts are held in extended position and in collapsed position under greatest tension. In other words, the tension under which the last parts are held to each other when the last is extended or when the last is collapsed, as the case may be, is greater than the tension under which the last parts are held when in an intermediate position.

Having thus fully described my invention, what I claim as new and desire to secure by Letters Patent is:—

In a last of the divided type, the combination of a heel part and a toe part, a lever pivotally attached to the heel part, a second lever pivotally attached to the toe part, a link extending from the heel part to the toe part and pivotally attached at its extremities to said levers, toggle mechanism carried by the free ends of said levers, and a spring interposed between said toggle mechanism and said link to maintain the last parts in extended position and in collapsed position under tension.

In testimony whereof I affix my signature. 105
CLINTON M. SEARL.
